18 Claims. (CL 250—20)

My invention relates broadly to oscillation systems and more particularly to a method and circuit arrangement for synchronizing local oscillations with respect to impressed oscillations.

5 The present invention is directed to improvements in methods whereby a first sinusoidal oscillation $S \sin(2\pi F_s t + \phi_s)$ is utilized for obtaining a second sinusoidal oscillation

$$H \sin(2\pi F_h t + \phi_h),$$

10 which is characterized in that its amplitude H and its phase difference from the first oscillation, namely $(2\pi F_h t + \phi_h) - (2\pi F_s t + \phi_s)$, are both substantially constant. In the case for instance, of 15 a message transmitted by wire or electromagnetic Hertzian waves, one of the oscillations is the carrier or pilot wave of the signal and it is required to obtain in the receiver a local oscillation which is in step with the carrier wave.

20 In all the arrangements enabling such a synchronous oscillation to be obtained, the receiving apparatus is provided with a circuit specially designed for the purpose, and the wave-band of which should be rendered as narrow as possible, 25 or the time constant as large as possible. Up to the present it has never been possible to make the band-width less than the sum f_s of the changes liable to affect one or the other of the frequencies F_h , F_s . In many instances this sum f_s is, itself, the 30 resultant of two kinds of superimposed changes: the one kind developing at an extremely slow rate but capable of attaining a very considerable amplitude $(f_s)_1$, in the long run—namely, the change progressively affecting the frequency of the transmitting station in relation to the oscillation generators of the receiver, by reasons of slow changes in the temperature of potential of the sources of supply. The other changes, $(f_s)_2$, are of much 35 smaller amplitude than the foregoing, but develop 40 or disappear far more rapidly, and arise for example, from modifications in the course of the Hertzian waves, or the slight mechanical tremors which inevitably affect the circuits of the transmitting and receiving stations. Hitherto, the receiving 45 circuits specially allocated to the production of the local synchronous oscillation had to have a band with a width at least equal to

$$f_s = (f_s)_1 + (f_s)_2,$$

50 or, which amounts to the same thing, a time constant inversely proportional to f_s . The term $(f_s)_1$ being by far the more important, it is desirable that it should be corrected independently by providing an arrangement that is specially intended 55 to modify, progressively, the regulating of one or more oscillation generators in the receiver, so as to adapt said regulation to the slow variations $(f_s)_1$ which the frequency F_s of the carrier or pilot oscillation undergoes. This forms the object of 60 the present invention, which consequently de-

scribes a new method and a manner of carrying it into effect.

According to the present invention the method broadly consists in so controlling the frequency of one of the said oscillations that gradual frequency changes are counteracted.

The method of my invention further comprises combining the said oscillations as to produce a physical agency slowly varying in accordance with the said gradual frequency changes, selecting said 10 slow variations of the physical agency and controlling thereby the frequency of one of said oscillations.

More particularly the method consists in combining in the receiver two devices, the first of 15 which is an arrangement controlling the frequency of the local generator by impressing on the frequency of one of the two oscillations H or S , a correction which from instant to instant compensates the frequency difference which the 20 very slow variations $(f_s)_1$ would tend to introduce between two frequencies F_h , F_s ; while the second device, which, when combined with the first one, has only to take account of the variation of greater rapidity but of very small magnitude, maintains 25 the two oscillations in step with one another.

The procedure, in accordance with this method, 30 consists in generating the local synchronous oscillation by utilizing for that purpose an oscillator connected with circuits which have a wave band having a width equal, or slightly superior, to the amplitude $(f_s)_2$ of the relatively rapid but slight frequency changes. Under these conditions, these are the best possible circuits, but, 35 after being in operation for a certain time they no longer suffice to correct the very slow variations, the magnitude $(f_s)_1$ of which becomes excessive after the lapse of a predetermined time interval. In proportion as the said magnitude 40 increases, the local synchronous oscillation would become progressively out of phase in relation to the control oscillation; the phase difference angle Ψ would vary and be subject to an error $\Delta\Psi$ the value of which would finally become 45 excessive. By the employment of suitable means, this error $\Delta\Psi$ is utilized for modifying the intensity of a current, or a difference of potential, and, by the agency of said current, or difference of potential, the regulation of an oscillation generator in the receiver is automatically controlled.

This control, the effect of which is to limit the error $\Delta\Psi$, is exercised through the agency of circuits which are distinct from the foregoing and have extremely large time constants, so as to respond 55 solely to the very gradual variations $(f_s)_1$.

The nature of my invention will be more fully set forth in the following specification by reference to the accompanying drawings, in which:

Figure 1 is a characteristic curve representing 60

the variations $(f_s)_1$ and $(f_s)_2$ —as a function of the time t —sustained by the carrier frequency F_s while functioning in the interval between the instants T_1 and T_2 ; Fig. 2 is a circuit diagram by which I have explained the coaction of local and incoming oscillations in a signal receiving circuit; Fig. 3 is a vector diagram showing the relation of values in the circuit of Fig. 2; Fig. 4 diagrammatically illustrates the system of my invention showing the means for separately correcting the very gradual variations of considerable amplitude which affect the carrier frequency; Fig. 5 diagrammatically shows a modified circuit arrangement embodying my invention; Fig. 6 is a vector diagram of the circuit illustrated in Fig. 5; Fig. 7 diagrammatically shows a circuit comprising a combination of the circuit arrangements shown in Figs. 2, 4 and 5, having means for the attainment of synchronism and the correction necessitated by the very gradual variations affecting the frequency of the carrier oscillation; and Fig. 8 illustrates a further circuit arrangement showing a modified form of the synchronizing system of my invention.

Referring to the drawings in detail, Fig. 1 shows a curve which has been plotted with time as the abscissa and frequency as ordinates. From the characteristic curve it will be seen that the mean value of the carrier frequency F_h varies slowly by $(f_s)_1$ periods, during the time interval T_1 : T_2 , and that the momentary value of said frequency undergoes—with regard to its mean value—fluctuations which are more or less rapid, but of small magnitude, not exceeding $(f_s)_2$ periods.

The synchronizing arrangement of Fig. 2 is the one forming the subject of my copending application Serial Number 574,858, filed November 13, 1931, entitled Synchronization system. The principle of this method will first be reviewed as a knowledge of the same is necessary for an understanding of the present invention. The signal, received at 2 synchronizes the local electron tube generator 3 which supplies the receiver with the synchronous oscillations necessary for its operation. In order to obtain this synchronism, both the signal and the electron tube generator 3 excite, either directly or through interposed circuits of any kind, an electron tube detector 1, the plate circuit of which comprises a resistance 6 shunted by a condenser 4, which may be replaced by a low pass filter. The time constant of the unit 4—6 is so determined as to pass, without appreciable weakening or change of phase, the currents varying at a frequency equal to or less than the variations $(f_s)_2$ represented in Fig. 1 and to suppress the currents varying at higher frequencies. Under these conditions the current in the resistance 6 is exclusively furnished by the mutual modulation of the local oscillation and the carrier oscillation, in the detector tube 1. This current has the form:

$$J = J_0 + kS \cos \psi.$$

In this expression J_0 is a mean current, k is a numerical coefficient depending on the sensitivity of the detector tube 1 and on the constant amplitude H of the local oscillation, S is the amplitude of the carrier or pilot oscillation, and ψ is the previously defined angle. So long as the frequencies F_h and F_s differ appreciably, regulation not having been effected, the term $kS \cos \psi$ represents an alternating current to which the D. C. milliammeter 10 does not respond, said milliammeter then indicating the mean current J_0 , which is thus easily known. On synchroni-

zation ($F_h = F_s$), the term $kS \cos \psi$ represents, on the contrary, a continuous current, the intensity $kS \cos (\Phi_h - \Phi_s)$ of which depends on the phase difference $\Phi_h - \Phi_s$. This current is utilized for controlling the frequency F_h of the generator 3. For example, the plate circuit of said generator is fed by the conductor 11 from the connection 7, the potential of which is determined by the value of the current J in the resistance 6. This potential across resistance 6 changes the effective plate potential of oscillator 3, thereby changing its internal plate conductance and therefore its frequency of oscillation. The frequency F_h of the generator 3 depends therefore, not only on the tuning of the main condenser 8 and its vernier adjustment condenser 9, but also on the current J and the angle ψ . Consequently, this frequency varies between a certain upper limit $F_h + f_h$ when the angle ψ is zero and the current $J_0 + kS$, and a certain lower limit $F_h - f_h$, when the angle ψ is equal to π and the current is $J_0 - kS$. It is assured for instance by suitably selecting the grid-bias connection 5, that the maximum correction $\pm f_h$ thereby applied to the frequency F_h of the generator 3, when the current J varies by $\pm kS$, will be at least 2 or 3 times greater than $(f_s)_2$. In the vector diagram of Fig. 3 the mean current J_0 is represented by the length 13, 14 and the current $kS \cos \psi$ by the length 14, 15—the projection on a fixed vector S of a vector H (of length kS) turning with the speed $2\pi(F_h - F_s)$ radians/second and forming the angle ψ with the preceding one. The current J varies therefore from the value

13, 12

(for $\psi = 180^\circ$) to the value

13, 16

(for $\psi = 0$). It has been demonstrated that this device is synchronized automatically by merely regulating the condensers 8, 9, and that this synchronization is most stable when the vector H is in the position H_0 , in quadrature with the vector S . This regulation is obtained by carefully adjusting the condenser 9 so as to bring the current reading in the milliammeter 10 to the mean value J_0 , whereupon

$$F_h = F_s, \psi = \frac{\pi}{2}$$

This regulation having been effected, the gradual variations $(f_s)_1$ represented in Fig. 1 tend progressively to nullify it. The gradual variation of the current J will be indicated by the milliammeter 10. In short, the maintenance of synchronization demands that every variation ΔF_s sustained by the carrier frequency should be counterbalanced, as it occurs, by an equal variation ΔF_h imparted to the frequency of the generator 3 by the control resulting from the connection 11. Since, by construction, a variation $\pm kS$ in the current J would correct the frequency F_h by the amount $\pm f_h$, it is necessary for said current to vary automatically, by the amount

$$\Delta J = KS \frac{\Delta F_s}{f_h}$$

in order to obtain the necessary correction $\Delta F_h = \Delta F_s$. This automatic variation is represented, in Fig. 3, by the length

14, 17.

The representative vector H has come into the position H' , forming with the normal position H_0 an angle $\Delta \psi$. At the end of a longer or

shorter period, the variation sustained by the carrier frequency attains a value $(f_s)_1$ for which the error in the angle ψ exceeds the permissible limit. With the circuit as shown in Fig. 2 it then becomes necessary to readjust the setting of the regulating condenser 9 by hand, in order to restore to the current J and angle ψ their normal values, J_0 and

10. $\frac{\pi}{2}$

Fig. 4 represents one form of circuit arrangement of my invention which performs these essential adjustments automatically. In addition to the elements already described and to the control, which through the agency of the conductor 11 compels the local generator 3 to follow the relatively rapid but low magnitude variations $(f_s)_2$, a second control is provided by the 20 variations in the resistance of the plate circuit of an auxiliary valve 19, coupled to the generator by a coil 18, as shown. The internal resistance of the valve 19 depends on the bias of its grid, or in other words (the switch 32 being set 25 in its normal position 34) on the potential of the condenser 20. This potential is governed by a relay 21, the armature 25 of which closes the circuit of said condenser, through a very high resistance 28, alternately through two connections 30 to different potentials on a suitable potential source, both connections 29 and 30 being negative in relation to that of the filament. The time constant of the unit comprising condenser 20 and resistance 28 may be equal 35 to several seconds. The potentials of the connections 29, 30 are such that, if they were successively transmitted to the grid of the valve 19, as would occur if the armature 25 rested successively on each of the contacts 26, 27 for any considerable time, the generator 3 would 40 produce, successively, two frequencies differing by several hundred periods. This difference is selected to exceed the variation $(f_s)_1$, eventually produced by the instability of the generators 45 during a long period of service. Given these conditions, it can easily be verified that the frequency F_h of the generator 3 varies in a very gradual manner, for example by some tenths of a period per second, so long as the armature 25 rests on one of the two contacts 26, 27 and that 50 the direction of this frequency variation is reversed when the armature passes from one of the contacts on to the other. The main winding 22 of the relay is traversed by the current J, and an auxiliary winding 23 is traversed by 55 an additional current, adjustable by a rheostat 24. The receiver is regulated in the following manner: at the commencement of the operation, when the frequencies F_s and F_h still differ considerably, the current in the milliammeter 10 has 60 the value J_0 . The switch 32 is set, provisionally, on the contact segment 33, which gives the grid of the valve 19 the polarization 31, that is, the mean between the connections 29 and 30. 65 The rheostat 24 is adjusted so that the armature 25 is in a state of equilibrium between the contacts 26 and 27, without touching either of them. The armature will subsequently pass through this position of equilibrium every time the current J resumes the value J_0 . As was explained 70 in my application, supra, describing the circuit according to Fig. 2, the condensers 8, 9 of the generator are tuned so as to obtain synchronism and to bring the vector H (Fig. 3) into the 75 position H_0 , in quadrature with the vector S.

The current J then resumes the value J_0 represented by the length

13, 14.

Finally the switch 32 is returned to the normal 5 position 34, as shown in Fig. 4.

The arrangement operates in the following manner: When this regulation has been effected the slow variation due to the instability of the generators tends to nullify it, and the current 10 J varies, therefore progressively, from the mean value J_0 . When it attains a certain value $J_0 \pm \Delta J$, that for example, represented by the length

13, 17.

15

the armature 25 comes to rest against the contact 26 or 27 and completes the circuit of the corresponding connection 29 or 30. This results in a gradual variation in the charge of the condenser 20, the polarization of the grid of the valve 19, and the frequency F_h of the generator 3. The representative vector, which is then in the position H' , begins to rotate in the suitable direction, which is ascertained by trial by reversing the connections 29 and 30 as required; the said vector returns towards the optimum position H_0 . The current J acquires a value more closely approximating to J_0 , the armature 25 moves away from the contact on which it has been bearing and the condenser 20, the circuit of which is again open, retains the acquired potential, until the gradual and uninterrupted variation of the carrier frequency F_h again requires the intervention of the relay. When, at the end of a very long time interval, for instance several hours, the milliammeter 35 indicates that the potential of the condenser 20 nearly attains one of the limits, 29 or 30, beyond which the automatic control would cease to function, the condenser 9 must again be regulated by hand, by 30 temporarily replacing the switch 32 in the position 33. The conductors 36 and 37 (Fig. 4) represent the feeders for the branch circuits for which the signal and the local oscillation are placed in phase before becoming rectified in the 35 second detector valve which permits the reception of the signal.

Another important observation must be made as regards the device illustrated in Fig. 4: It has been stated that "the rheostat 24 is adjusted 50 so that the armature 25 is in a state of equilibrium between the contacts 26 and 27, every time the current J resumes the particular value J_0 ." Now, according to the relation $J = J_0 + KS \cos \psi$, said particular value J_0 is resumed by J, both 55 when $\psi = 90^\circ$ (normal value), or when $S = 0$ (as happens for instance during a deep fading). So, a temporary suppression of control during fading does not affect in any way the local oscillation's frequency F_h . As long as the intensity 60 of S remains very small, the circuit of condenser 20 is open, owing to relay 21; said condenser keeps up the potential which it had at the very moment fading began; and the local generator 3 keeps up provisionally the particular frequency 65 F_h imposed on it by said constant potential. Thus, temporary suppressions of control during fading do not change in any way the local generator's frequency. It is quite the reverse of what happened with the frequency control systems previously known.

Summarizing the above-described circuits and operations, it is desired to synchronize a local oscillation $H \sin (2\pi F_{at} t + \Phi_h)$ with a controlling oscillation $S \sin (2\pi F_s t + \Phi_s)$. To obtain such a 75

result, the frequency F_h must necessarily depend in some way either on the phase difference ψ for perfect synchronism as illustrated and described in my copending application Serial No. 574,858, or on the difference of frequency $F_h - F_0$. The following explanations relate to both methods of control, but for purposes of illustration, I shall consider only the method which utilizes the phase difference ψ .

10 In Fig. 2 the control exerted upon the local frequency F_h by the current J equals $J_0 + KS \cos \psi$ and by the conductor 11 is given by:

$$F_h = F_0 + \text{function } (\psi)$$

15 where F_0 designates the proper frequency which would be taken by generator 3, if the controlling oscillation received by 2 should be non-existing. This is the condition obtained when there is an extended fading interval and S then equals 0. 20 In other words, F_0 is the frequency of the generator when the current recorded on milliammeter 10 has the value J_0 , independent of the controlling oscillation. This is a clear and concise definition of F_0 . Function (ψ) is the correction imposed by current J on the local frequency when said current passes from J_0 to any other particular value $J_0 + KS \cos \psi$; i. e. when the variation of the current J is $KS \cos \psi$. In practice, these frequency corrections are small, 25 and the proportional relation:

$$\text{function } (\psi) = f_0 \cdot KS \cos \psi$$

is obtained, in which f_0 designates the correction imposed on the local frequency F_h by a unit variation of current J . f_0 is readily measured 35 and modified, for instance, by changing resistance 6 or by choosing an adequate electron tube 3; but this being done and the apparatus once constructed, f_0 is a constant. From the above it is clear that when the two oscillations are in synchronism, the equation of this synchronism is:

$$F_h = F_0 + f_0 \cdot KS \cos \psi \quad (1)$$

This equation signifies that the difference $F_h - F_0$ between the controlling frequency F_h and the generator's proper frequency F_0 is at any time compensated by the correction $f_0 \cdot KS \cos \psi$ imposed on said generator by the detected current $KS \cos \psi$ resulting from the controlling oscillation.

50 This equilibrium is only possible when

$$F_h - F_0 < f_0 \cdot KS \quad (2)$$

So long as condition 2 is satisfied, the two oscillations automatically maintain a fixed phase relation or phase different ψ , given by

$$\cos \psi = \frac{F_h - F_0}{f_0 \cdot KS} \quad (3)$$

But when $F_h - F_0 > f_0 \cdot KS$, synchronism is no longer obtained since it is impossible that $\cos \psi$ ever be greater than 1. In that case the interfering current $KS \cos \psi$, whose frequency was previously 0 suddenly becomes oscillatory. When this frequency becomes too high, the current is stopped by the condenser 4 or by the low-pass filter and no longer passes through resistance 6. The two oscillations then become independent of each other and resume their natural frequencies F_h and F_0 respectively.

70 With this brief summary in mind, Fig. 2 showing a single control and Fig. 4 showing a double control of the present application will now be considered. In Fig. 2, at the initial time T_1 (Fig. 1), the operator has adjusted condensers 8, 9, so as to bring the two oscillations into quadrature, i. e.,

to obtain a current J , as indicated in milliammeter 10, having the particular value J_0 . According to Equation 3, if ψ equals 90° , $\cos \psi$ equals 0 and the proper frequency F_0 of the local generator 3 is equal to the control frequency F_0 . 5

As illustrated in Fig. 1, F_h now begins to vary with respect to F_0 . Phase difference ψ automatically deviates from the initial value 90° and approaches 0° or 180° . From Equation 3, it will be evident that in order to keep the change in phase difference ψ as small as possible for fluctuating values of F_h , it is necessary to give $f_0 \cdot KS$ a large value. For example, should the device be working four hours without any supervision and should slow variation $(f_s)_1$ of control frequency F_h reach 15 200 cycles, i. e. $[(f_s)_1 = 200]$ at the end of said lapse of time, a correction of 1,000 cycles ($f_0 \cdot KS = 1,000$) would be necessary to prevent the variation of angle ψ from exceeding 12° , for instance:

$$(\cos \psi) = \frac{F_h - F_0}{f_0 \cdot KS} = \frac{200}{1000} = 0.2; \psi = 78^\circ = 90^\circ - 12^\circ$$

On the other hand, so large a correction as $f_0 \cdot KS$ equals 1000 cycles, results in a sacrifice in accuracy. If $KS = 1$ millampere (current recorded in 10 varying 1 millampere when ψ passes from the normal value of 90° to the limit 180°), the equation $f_0 \cdot KS = 1000$ implies that a 0.1 millampere variation of the detected current imposes a 100 cycles correction to the local frequency F_h . Such a high value of f_0 results in the synchronism no longer being well protected against electromagnetic perturbations arriving through conductor tubes. 30

In spite of the excellent selection insured by 35 condenser 4 (in homodyne reception 4,6 acting as a resonator) or by the low pass filter, such perturbations produce small variations Δj of the current J in resistance 6 and according to the definition of f_0 , these accidental variations of Δj impose variations $f_0 \Delta j$ on the local frequency. From this point of view, the high value of f_0 is undesirable.

Let us now suppose that, at a given time T_2 (Fig. 1) the difference $F_h - F_0$ equals 100 cycles. If $f_0 \cdot KS$ equals 1000, $\cos \psi = 0.1$ and $\psi = 84^\circ$. The working of the device appears to be good. But if there is a long fading interval not compensated by automatic volume control, S becomes very weak and synchronism expressed by Equation (3) no longer exists since $\cos \psi$ cannot exceed 1. The two oscillations become independent of each other and the interfering current frequency passes from 0 to 100 cycles. Such frequency is usually audible in spite of the weakening of S and furthermore, it exceeds the band width of 4.6 (or of the low-pass filter) and prevents the synchronizing current from reaching resistance 6. When fading is over, synchronism is not restored automatically and the operator must readjust condensers 8 and 9. 50

To sum up, a synchronization obtained by the agency of a single uniting connection or control is limited in operation. Given the important variation $(f_s)_1$ of the control frequency F_h , $f_0 \cdot KS$ must have a very high value and difficulties result 65 therefrom. Accordingly, the double control described in my present application is very desirable. Considering now Fig. 4, it will be noted that current $J = J_0 + KS \cos \psi$ recorded in 10 takes on the same value J_0 either when the working is perfect 70 ($\psi = 90^\circ$) or when a fading temporarily suppresses the controlling oscillation ($S = 0$). In both cases the control provided for compensating the slow variation $(f_s)_1$ of F_h is temporarily suppressed, the armatures 25 of relay 21 being then halfway 75

from 25 and 26, and the circuit of condenser 28 being open. Said condenser then acts as a biasing source of provisionally constant potential. F_0 again designating the proper frequency of generator 3, when independent from the controlling oscillation, it will be seen that the value of F_0 at a given time now depends not only on the actual adjustment of condensers 8, 9 but also on the potential acquired by condenser 26. Should condensers 8, 9 be adjusted by hand or should the potential of condenser 26 be automatically modified, the result will be exactly the same, i. e., F_0 will be modified.

The part played by the slow uniting connection 15 22, 21, 25, 28, 20, 19, 18, can therefore be described as follows: this part is intermittent; as long as ψ is very close to 90° (for instance, $85.5^\circ < \psi < 94.5^\circ$) the connection is cut off; but as soon as ψ somewhat differs from 90° , $KS \cos \psi$ from zero and J 20 from J_0 , the uniting connection resumes its part, modifies F_0 and brings back J within the chosen limits. This leads exactly to the same result as when an operator frequently adjusts the condensers 8, 9 and thus compels the generator's 25 proper frequency F_0 to follow the control frequency's low variations (f_s)₁.

The fundamental difference between Fig. 2 and Fig. 4 resides in the fact that in Fig. 2 the proper frequency F_0 is a constant whereas in Fig. 4 this 30 frequency is a broken line practically indistinguishable from the average value of F_0 . The part played by the other control 11 is now merely to maintain the synchronism of two oscillations whose proper frequencies F_1 and F_0 only differ 35 from each other by the small rapid variations (f_s)₂ of F_0 . According to Equation (3), the maximum correction of $f_0 \cdot KS$ which connection 11 has to insure, is but very small, for example $6(f_s)_2$, and the drawbacks of Fig. 2 are avoided.

40 Synchronism is protected in the best possible manner against any kind of electromagnetic interference: indeed, the slow control 22 . . . 18 is non-responsive to such interference owing to the slowness of relay 21 and to the high time constant 45 28, 20. The other control is not much more sensitive to this interference, as the band width of selecting circuit 4, 6 and the maximum correction $f_0 \cdot KS$ are exclusively imposed by the small variations (f_s)₂ and therefore are small themselves.

50 When a fading renders the signal inaudible, it does not matter very much whether or not the oscillations temporarily fall out of synchronism: no hissing due to interference can be heard since the differential frequency $F_1 - F_0$ is only of about 55 1 cycle. As soon as fading is over, the two oscillations automatically come again into synchronism. The whole of the above description can be applied without any modification to the other case, where the synchronizing current is a function, not of the phase difference ψ , but of the difference of frequency $F_1 - F_0$.

In most receivers, the frequency of the signal is modified by a heterodyne. In such case, if F_1 be employed to designate the frequency of the 60 carrier or pilot oscillation, as received by the antenna, and F_2 to represent the frequency of the heterodyne, the new frequency F_s acquired by the carrier oscillation on arriving at the detector valve 1 will be $F_s = F_1 - F_2$, and depends therefore 65 on the frequency of the heterodyne. It is evident that the synchronism obtained in Fig. 2 by controlling the frequency F_h of the local generator 3 by means of the conductor 11, may equally be obtained by controlling the frequency F_2 of the 70 heterodyne by means of the same conductor. 75

This modification is represented in Fig. 5, in which the frequency F_1 of the signal received at 2 is modified by the heterodyne 38. The signal, of which the carrier oscillation, $S \sin(2\pi F_s t + \phi_s)$, acquired the new frequency F_s as delivered by the 5 output of the detector 39, is transmitted by suitable circuits, 40 to the detector 1, in which it interferes with the synchronous local oscillation $H \sin(2\pi F_h t + \phi_h)$ furnished by the generator 3. The current in the resistance 6 has the same 10 value $J = J_0 + k \cdot S \cos \psi$, as before. Through the conductor 11, the connection 7 controls the frequency F_2 of the heterodyne 38 and therefore the differential frequency F_s of the carrier oscillation. The explanations furnished respecting Fig. 15 3 in my patent application describing the arrangement of Fig. 2 may also apply to Fig. 6 in which the vector H , representing the local oscillation, is now stationary, whereas the vector S representing the heterodyned carrier oscillation 20 of the signal becomes mobile. In practice, in order to obtain synchronism and then place the representative vector S in quadrature in the optimum position S_0 , in which the current J read off in the milliammeter 10 regains the mean value 25 J_0 , represented by the length 13, 14, either the condensers 8, 9 of the synchronous generator 3 or the condenser 41 of the heterodyne, may be regulated at will.

Consequently the arrangement represented in 30 Fig. 4 may be modified as shown in Fig. 7, in which the control established by the conductor 11 acts, as before on the synchronous generator 3, while the control established by the coil 18 and valve 19 acts on the heterodyne 38. The conductor 11 compels the frequency of the generator 3 to follow the variations relatively rapid, but of small magnitude, (f_s)₂ sustained by the carrier frequency F_s . On the other hand, these variations are not transmitted to the valve 19, on account of the very high time constant of the assembly formed by the resistance 28 and condenser 20, but this assembly 28, 20 transmits to the valve 19 the variations of potential applied, at the connection 1, by the progressive variations of the current J resulting from the extremely gradual variations (f_s)₁ due to the possible instability of the transmitting station. Hence the double control functions in the manner already described. 45

Fig. 8 shows how the invention is applied when 50 the synchronous local oscillation is obtained by the method described in the United States Patents Nos. 1,491,372 and 1,722,789, and application Serial Number 185,813, and others. In this method the signal received at 2 interferes, in the 55 detector tube 39, with the heterodyne 38, and in the circuit 40, its carrier frequency assumes the differential frequency F_s . The circuit 40 supplies two branches. The branch 42 excites the detector valves 43 and 52, which receive the complete 60 signal comprising the heterodyned carrier oscillation and the signal oscillations distributed in the adjacent bands. By means of a valve 45, the other branch 44 excites a resonator or band pass filter 46, tuned to the frequency F_s and constructed 65 so as to allow the frequencies comprised between $F_1 - (f_s)_2$ and $F_1 + (f_s)_2$, where (f_s)₂ represents the variations of Fig. 1, to pass without any notable change of phase. The width $2(f_s)_2$ of the band being extremely small, the circuit 46 70 arrests the signal oscillations contained in the adjacent bands, and transmits to the valve 41, only the continuous oscillation due to the action of the carrier oscillation. This continuous oscillation is therefore a synchronous local oscil- 75

lation. A phase corrector, for example an artificial line 48 along which the contact 49 is moved, enables this local oscillation to be brought into phase, in the detector 43, with the carrier oscillation of the signal arriving through the conductor 42. Synchronous reception is thus assured, in the usual manner in the indicator apparatus 50.

Hitherto, the working of this arrangement was rendered impossible by the variation (f_0)₁ due to the instability of the transmitting station. Under the influence of these variations, the frequency of the carrier oscillation soon ceases to lie within the limits of the band of the filter 46 and the continuous oscillation sustained a phase displacement rendering reception impossible. This is remedied by disposing on the artificial line 48 a second contact 51 which is adjusted, at the same time that the receiver is regulated, so that in the detector valve 52 the local oscillation is in quadrature in relation to the signal admitted by the conductor 42. The current $J = J_0 + k.S.\cos\psi$ read off on the milliammeter 18 then assumes the mean value J_0 , and deviates on either side of this mean according as the carrier frequency deviates from the value F_0 for which the filter 46 is designed. In fact, the phase of the oscillation transmitted by said filter then varies by a certain amount $\pm\Delta\psi$, and the current J assumes the new value:

$$J = J_0 + k.S.\cos\left(\frac{\pi}{2} \pm \Delta\psi\right) \approx J_0 \pm kS\Delta\psi.$$

The current variations actuate the relay 21, and through its agency, the frequency of the heterodyne 38, until the differential carrier frequency again exactly acquires the value F_0 , at which the current J returns to the mean value J_0 . This control is operated similar to the arrangement shown in Fig. 4.

The system of my invention has been found to be positive in its operation and extremely accurate in the maintenance of predetermined phase relation between the impressed oscillations and the locally generated oscillations. I have described my invention in certain of its preferred embodiments but it will be understood that modifications may be made and that no limitations upon my invention are intended other than are imposed by the scope of the appended claims.

What I claim as new and desire to secure by Letters Patent of the United States is as follows:

1. A method for maintaining an approximately constant phase difference between two oscillations, the frequencies of either or both of which may undergo very gradual but relatively large changes superimposed on changes of greater rapidity but of lesser magnitude, which comprises so combining in an electron tube circuit the two oscillations as to produce an interference current whose intensity, depending upon the said phase difference, admits simultaneously of very progressive variations produced by said gradual frequency changes, and of more rapid variations produced by said more rapid frequency changes, utilizing through suitable means said more rapid intensity variations to exert on the frequency of one of said oscillations a first control compelling this oscillation to follow the small but rapid frequency changes of the other oscillation, whereby the two oscillations are synchronized; and furthermore utilizing through separate means, said very progressive intensity variations of the said interference current to

exert a second frequency control whereby the normal value of the phase difference is maintained.

2. In a system for maintaining an approximately constant phase difference between two oscillations, the frequencies of either or both of which may undergo very gradual but relatively large changes superimposed on changes of greater rapidity but of lesser magnitude, means for effecting locked synchronism between the oscillations comprising a circuit having a band width corresponding with the magnitude of the said more rapid frequency changes, said circuit operating to control the frequency of one of said oscillations to counteract said rapid frequency changes, and means operated by the very slow phase displacements produced between the two so synchronized oscillations by the said gradual frequency changes for controlling the frequency of said one of said oscillations so as separately to counteract the said gradual changes, both of said controlling forces being simultaneously operable.

3. In a system for maintaining an approximately constant phase difference between two oscillations, the frequencies of either or both of which may undergo very gradual but relatively large changes superimposed on changes of greater rapidity but of lesser magnitude, a circuit arrangement including a detector in which said two oscillations are mutually modulated, means for producing a synchronizing current by the mutual modulation having an amplitude depending upon the said phase difference and which admits simultaneously of very gradual variations produced by the gradual frequency changes and more rapid variations produced by the more rapid frequency changes, a selecting circuit for selecting said synchronizing current, the band width of said circuit extending from zero to a limit corresponding with the small magnitude of the more rapid frequency changes, and means connected with said selecting circuit providing two separate controls whereby the normal phase difference is maintained, one of said controls being exerted through a device having a very large time constant so as to be exclusively responsive to the very gradual variations in the amplitude of the synchronizing current.

4. In a system for maintaining a normal phase difference between two oscillations, the frequencies of either or both of which may undergo very gradual but relatively large changes superimposed on changes of greater rapidity but of lesser magnitude, circuits comprising a detector in which the two oscillations are mutually modulated, means for deriving from said mutual modulation a synchronizing current of amplitude varying approximately as the projection of the vector representing one of said oscillations upon the vector representing the other oscillation, a circuit in the output of the detector constituting a selecting path for continuous and low frequency currents, so as to accurately transmit the most rapid variations in the amplitude of the synchronizing current, and means connected with said circuit providing two separate controls whereby the normal phase difference is maintained, one of said controls being exerted through a device having a very large time constant, so as to be exclusively responsive to the very gradual variations in the amplitude of the synchronizing current.

5. In a system for maintaining a normal phase difference between a local oscillation and a received oscillation whose frequency may undergo

very gradual but relatively large changes superimposed on changes of greater rapidity but of lesser magnitude, a circuit comprising a local heterodyne generator operating to modify the frequency of the received oscillation, a selecting circuit actuated by said modified received oscillation, the band width of said selecting circuit being approximately equal to the magnitude of the more rapid frequency changes, a local synchronous oscillator, means whereby said rapid frequency changes govern the frequency of said local synchronous oscillator to counteract said rapid frequency changes, and means whereby the very slow phase displacements produced in said selecting circuit by the very gradual but large frequency changes govern the frequency of the heterodyne generator so as to counteract said phase displacement.

6. A method of frequency control, to counterbalance the variations which affect the relative frequency of two oscillations separately generated, said variations due to very gradual but large changes superimposed on changes of much greater rapidity but of small amplitude usually undergone by the natural frequencies of either or both of these oscillations, which consists in maintaining the normal relative frequency of the oscillations by way of two separate frequency controls, a first one of small magnitude but of sufficient rapidity to counterbalance the said small but rapid frequency changes, and a second one very progressive but of large magnitude to separately counterbalance the said gradual but large frequency changes.

7. The method for maintaining a constant frequency relation between two oscillations, the natural frequencies of either or both of which may admit very gradual but relatively large changes superimposed on changes of greater rapidity but of lesser magnitude, which comprises providing a first control for exclusively compelling one of these oscillations to follow the small but rapid frequency changes undergone by the other one, combining the oscillations so as to produce a variable resultant current varying under the joint control of the coaxing oscillations, and utilizing the resultant current for actuating a second control whereby the gradual but large frequency changes are separately neutralized.

8. A method of synchronizing two oscillations, the frequencies of either or both of which may undergo very gradual but relatively large changes superimposed on changes of greater rapidity but of lesser magnitude, which comprises, insuring by one frequency control means the synchronism of the oscillations exclusively against the said rapid but small frequency changes, and furthermore producing by the combination of the so synchronized oscillations a variable current whose variations, when exceeding two predetermined limits, exert on the frequency of one of these oscillations through separate frequency control means a very slow operative control, whereby the said current is restored within the said limits.

9. A method of frequency control for maintaining a normal frequency relation between a received oscillation and a local oscillation, the frequencies of either or both of which may undergo very gradual but relatively large changes superimposed on changes of greater rapidity but of lesser magnitude, which comprises, insuring by one frequency control means the synchronism of the oscillations exclusively against the said

rapid but small frequency changes, and furthermore producing in a suitable circuit by the joint action of the so synchronized oscillations a variable current whose intensity resumes a particular value when the amplitude of the received oscillation is zero, and when the frequency relation is normal, said variable current, when exceeding two predetermined limits situated on either side of the said particular value, being utilized to exert on the frequency of one of the synchronized oscillations through separate frequency control means a very slow and discontinuous control whereby the said current is restored within the said limits.

10. In a synchronizing system, a source of oscillations of varying frequency, a second source of variable frequency; means under the joint control of said sources for producing a current fluctuating in amplitude over a predetermined range in accordance with the relative frequency fluctuations of said sources, means whereby said current controls the frequency of said variable source, there being a predetermined relationship between each value of said current and the resulting frequency of said controlled source, and means for varying said predetermined relationship of said current and said frequency whereby a same value of current produces a different frequency of said controlled source.

11. A system for maintaining a normal frequency relation between a local oscillation and a received oscillation issued from a Hertzian wave whose frequency may fluctuate rapidly with reference to a slowly variable mean value, which comprises means for producing a synchronizing current from the interference of the said oscillations, means for selectively transmitting the most rapid intensity fluctuations of this current, a plurality of means constituting frequency controls, one of said control means being disposed in the output of said selecting means and responsive to the rapid fluctuations of the synchronizing current, another of said control means being slowly operative when the mean value of this current departs from zero.

12. A system for maintaining a local oscillation in quadrature with a second oscillation issued from a received wave, which comprises: means for producing by interference of these oscillations a synchronizing current whose intensity is zero when the said oscillations are in quadrature; a relay having an armature, a contact on each side thereof, and a main winding; a circuit forming a path for said synchronizing current and including said winding, said armature being movable between said contacts, two biasing circuits respectively connected with the said contacts; adjusting means whereby one of said biasing circuits or the other is closed by the armature according as the synchronizing current is positive or negative, both circuits being opened when the said current is zero; a plurality of means constituting frequency controls, one of said control means being responsive to the action of the synchronizing current through electrical circuits, another of said control means being operative to increase or lessen the controlled frequency according as one or the other of the said biasing circuits is closed by the armature.

13. In a device where two separately generated waves are coaxing, the method of maintaining these waves at a predetermined frequency relation which comprises detecting unbalance in this frequency relation, simultaneously providing from the detected unbalance a plurality of elec-

trically independent frequency correcting controls operative in cooperation for controlling the generation of the waves so as to substantially neutralize this unbalance, and proportioning two at least of these controls to be operative over different ranges of frequency corrections.

14. In a device where two separately generated waves are coating, the method of maintaining these waves at a predetermined phase relation which comprises detecting unbalance in this phase relation, causing the detected unbalance to act on the generation of the waves through a plurality of electrically independent paths so as to substantially neutralize the unbalance by controlling the frequencies of the waves, and supplying two at least of the independent paths with different time constants.

15. In a system utilizing two separately generated waves, the method of maintaining a predetermined frequency relation between these waves characterized by controlling the frequency relation therebetween relatively slowly over a frequency range and simultaneously controlling the same more rapidly over a narrower frequency range.

16. In a receiver in which a resultant electric wave is derived from the interference of the received wave with a generated heterodyning wave, the method of frequency control which comprises locally generating an electric oscillation, combining the locally generated electric oscillation with the resultant wave to derive a frequency correcting current, deriving from this current two substantially independent frequency correcting controls for individually controlling the generation of the heterodyning wave and the generation of the local oscillation, and proportioning the control on the heterodyning wave so as to be operative over a larger range of frequency corrections and at a slower rate of action as compared to the control on the local oscillation.

17. In a receiver where a received wave coacts with a locally generated heterodyne wave, the method of controlling the frequency relation of these waves which comprises beating the received wave and the heterodyne wave for producing a resultant oscillation, locally generating an auxiliary oscillation tuned to this resultant oscillation, beating the resultant and auxiliary oscillations for producing a frequency controlling current, individually applying to the generation of the auxiliary oscillation and to the generation of the heterodyne wave two substantially independent frequency correcting controls both established by the frequency controlling current, controlling the auxiliary oscillation by the frequency controlling current so as to maintain this oscillation in locked synchronism with the resultant oscillation, further controlling the heterodyne wave by the frequency controlling current so as to substantially annul the mean intensity of the frequency controlling current, and proportioning the control of the heterodyne wave so as to be operative over a larger range of frequency corrections and at a slower rate of action as compared to the control of the auxiliary oscillation.

18. The method of frequency control which comprises generating an electric wave, determining changes in the frequency of this wave, simultaneously applying to the generation of the wave two substantially independent frequency correcting controls both established by the determined changes, proportioning one of these controls to be operative over a smaller range of frequency corrections and at a relatively faster rate of action as compared to the other control, and arranging the slower acting control so as to cause the faster acting control to operate substantially at the mean frequency of its frequency range of operation.

HENRI JEAN JOSEPH MARIE DE
REGNAULD DE BELLESIZE.
